DESIGN FOR A FAN CASING

Junius W. Houston, Defiance, Ohio, assignor to
The Defiance Alloyed Products Company, a
corporation of Ohio

Application August 28, 1941, Serial No. 103,073

Term of patent 3½ years

To all whom it may concern:

Be it known that I, Junius W. Houston, a citizen of the United States of America, residing at Defiance, county of Defiance, and State of Ohio, have invented a new, original, and ornamental Design for a Fan Casing, of which the following is a specification, reference being had to the accompanying drawing, forming a part thereof, wherein:

Figure 1 is a top plan view of a fan casing, showing my new design.

Figure 2 is a side elevational view.

Figure 3 is an end elevational view rotated through an angle of 90°.

I claim:

The ornamental design for a fan casing, as shown.

JUNIUS W. HOUSTON.
